UNITED STATES PATENT OFFICE.

HAROLD D. HENDERSON, OF YARRAVILLE, VICTORIA, AUSTRALIA.

CONCRETE-BLOCK MOLD.

1,360,214.

Specification of Letters Patent. Patented Nov. 23, 1920.

Application filed January 7, 1920. Serial No. 349,892.

To all whom it may concern:

Be it known that I, HAROLD DUDLEY HENDERSON, a subject of the King of Great Britain, residing at Morven Street, Yarraville, in the State of Victoria and Commonwealth of Australia, have invented new and useful Improvements in Concrete-Block Molds, of which the following is a specification.

10 This invention consists of an improved mold for use in the manufacture of concrete and other composite blocks for building purposes, and has been devised for the purpose of enabling such blocks to be easily and 15 quickly made by unskilled labor and at much less cost than at present. A further advantage is that the block can be removed from the mold without first dismantling it, which is necessary with other molds in use 20 at present.

My improved mold consists of two parts, viz: the mold proper, and a removable portion which fits therein. The mold proper consists of a metal frame composed of two 25 vertical sides and a bottom. Rigidly attached to the said bottom are two or more vertical metal cores, said cores being for the purpose of forming cored openings to constitute air passages in the building blocks 30 made in said mold, and, at the same time, lessening the weight of the blocks. The removable portion, which fits within the mold proper, consists of a false bottom having upwardly extending ends, which, when said removable portion is in position within the 35 mold proper, constitute the ends thereof. The removable portion is an important feature of the invention, as, by means of it, the concrete block can be easily and quickly removed from the mold proper when made.

Referring now to the two sheets of drawings hereto annexed:—

Figure 1 is a perspective view of the mold proper.

45 Fig. 2 is a perspective view of the removable portion, shown removed from the mold proper.

Fig. 3 is a longitudinal vertical section of the mold filled with concrete to form a building block.

50 Fig. 4 is an underside plan view of the mold.

Fig. 5 shows a view of the mold proper raised clear of the removable portion containing the block, the said removable por-

tion being shown in section to illustrate the receptacles for the cores attached to the bottom of the mold proper.

Fig. 6 is a perspective view of the block after removal from the mold.

60

Fig. 7 is a perspective view of a modified form of mold for use in the manufacture of blocks with an ornamental face.

1 are the vertical sides of the mold proper having an angle flange 2 riveted to the top edge of each. The bottom edge of each of the said vertical sides is bent inward toward one another to constitute flanges 3, which form the bottom of the mold proper. 4 are

65

cores rigidly attached to said bottom flanges 3, for the purpose of forming cored openings 5 in the block shown in Fig. 6. The cores 4 being rigidly attached to the bottom flanges

70

3 keep the vertical sides 1 in position, and so prevent any possibility of their spreading.

75

The said vertical sides 1 are further connected together by means of suitable tie bars 6 which also form handles to facilitate the handling of the mold. The removable portion of the mold, illustrated more particu-

80

larly in Fig. 2, comprises a bottom plate 7 and end vertical plates 8 one of which is shown hinged to the bottom plate 7 by hinge

90

9 to facilitate the removal of said removable portion from the block, as illustrated in Fig. 5. Each end vertical plate 8 is fur-

85

nished with a bracket 10 and a clip 11. The said brackets 10 and the top flanges 2 lie in the same plane when the mold is in the position shown in Fig. 3, and provide an even

90

surface for a scraper to pass over them to remove the surplus material from the top of the mold, as will hereinafter be described. The bottom plate 7 of the removable portion

95

of the mold is furnished with openings 13 which correspond to the shape of the cross section of the cores 4 in the mold proper.

100

These openings enable the removable portion to be readily placed in position within the mold proper (as shown in Fig. 3), and removed therefrom when required. When the removable portion is in position within

105

the mold proper, the end plates 8 of the latter bear against the vertical sides 1 of the former, and thus prevent any lateral move-

110

ment of the removable portion. The said end plates 8 also bear against the tie bars 6 thus preventing the removable portion moving longitudinally of the mold proper when

the concrete or composite material is fed

thereto. The said clips 11 on the end plates 8 also engage one pair of the tie bars 6 (see Fig. 3) and thus prevent any liability of the end plates 8 collapsing inward. It will thus be understood that when the removable portion is in position within the mold proper, the whole forms a practically rigid mold.

In the modified construction of mold, illustrated in Fig. 7, and which is adapted for use in the manufacture of a block having one of its faces ornamented, one of the vertical sides 1 of the mold proper is hinged to the outer edge of the adjacent angle flange 3, and the inner face of said hinged plate may 10 have formed thereon either in intaglio or rilievo, any suitable design which it is desired to impress upon the face. In order to 15 get a clear-cut impression, it is advisable that said hinged plate should be made of 20 brass.

It is of course to be understood that molds made according to my invention may vary both in size and shape in order to suit various requirements.

25 The mode of operation is as follows: The mold proper, having been placed in the position shown in Fig. 1, the removable portion (shown in Fig. 2) is inserted within it, so that its bottom plate rests upon the flanges 30 constituting the bottom of the mold proper. The removable portion is then filled with concrete or other composite material, as 35 illustrated in Fig. 3, any surplus material being removed by means of a scraper being passed along the flanges 2 and brackets 10. The mold is reversed, that is to say, it is turned into the position shown in Fig. 5, the tie bars or handles 6 assisting in the opera-

tion. The operator then places his feet on the brackets 10 and lifts the mold proper, by 40 means of the said handles, away from the removable portion containing the block. He then opens outward the hinged vertical plate 8, when said removable portion can be lifted clear of the molded block, which, after being 45 allowed to dry, is ready for use.

I claim:—

1. In a mold for use in the manufacture of concrete and other composite blocks for building purposes, a mold proper comprising 50 two vertical sides, an outwardly projecting flange at the top edge of each, the bottom edge of each vertical side being bent inward toward one another to constitute flanges, 55 cores rigidly attached to said bottom flanges, and tie bars for connecting said vertical sides together.

2. In a mold of the class described, the combination with the mold proper defined by claim 1, of a removable portion comprising 60 a bottom plate having openings therein which correspond to the shape of the cross section of the cores in the mold proper, vertical plates at each end of said bottom plate, one of said vertical plates being hinged, and 65 each end being provided with a bracket and clip, as and for the purpose described.

3. A mold of the kind defined by claim 1 in which one of the vertical sides of the mold proper is hinged to the outer edge of the adjacent bottom angle flange, said hinged side having formed thereon, either intaglio or 70 rilievo, any suitable design as and for the purpose described.

HAROLD D. HENDERSON.
